(57) **CLAIM**

The ornamental design for a propulsion board assembly, as shown and described.

DESCRIPTION

FIG. 1 is an exploded top view of the propulsion board assembly right side;

FIG. 2 is an exploded bottom view thereof;

FIG. 3 is an exploded left edge view thereof;

FIG. 4 is an exploded right edge view thereof;

FIG. 5 is an exploded side view thereof;

FIG. 6 is an exploded side view thereof;

FIG. 7 is a top view thereof; and,

FIG. 8 is a bottom view thereof.

The broken lines in the drawings depict portions of the propulsion board assembly that form no part of the claimed design.
